(57) **CLAIM**

The ornamental design for a computer display screen or portion thereof with animated graphical user interface, as shown and described.

DESCRIPTION

FIG. 1 is a front view of a computer display screen or portion thereof with animated graphical user interface showing the first image in a first embodiment of the claimed design; FIG. 2 is a front view showing the second image thereof; FIG. 3 is a front view showing the third image thereof; FIG. 4 is a front view of a computer display screen or portion thereof with animated graphical user interface showing the first image in a second embodiment of the claimed design; FIG. 5 is the second image thereof;

FIG. 6 is the third image thereof;

FIG. 7 is a front view of a computer display screen or portion thereof with animated graphical user interface showing the first image in a third embodiment of the claimed design; FIG. 8 is the second image thereof;

FIG. 9 is the third image thereof;

FIG. 10 is a front view of a computer display screen or portion thereof with animated graphical user interface showing the first image in a fourth embodiment of the claimed design;

FIG. 11 is the second image in the fourth embodiment of the claimed design; and,

FIG. 12 is the third image in the fourth embodiment of the claimed design.

The appearance of the transitional image sequentially transitions between the images shown in FIGS. 1-3, 4-6, 7-9 and 10-12, respectively, for each of the illustrated embodiments. The process or period in which one image transitions to another image forms no part of the claimed design.

The longer broken-line showing of a portion of a computer and the intermediate-length broken-line showing of a display screen of the computer, as well as the features within the interface shown in still shorter broken-lines, are included for the purpose of illustrating environmental structure and form no part of the claimed design.

1 Claim, 12 Drawing Sheets
